UNITED STATES PATENT OFFICE.

EDWARD HASKINS SHACKELFORD, JR., OF JOPLIN, MISSOURI, ASSIGNEE TO HEBBARD MANUFACTURING COMPANY, OF JOPLIN, MISSOURI, A CORPORATION OF MISSOURI.

SCREEN-VIBRATING MECHANISM.

Application filed August 5, 1926. Serial No. 127,314.

This invention relates to vibrating screens such as are used with concentrators and particularly to the means for giving vibration to the screen.

5 The general object of the present invention is to provide a screen vibrating means including a reciprocating rod preferably operated by an eccentric but not necessarily so, and means whereby the reciprocations of this rod may be transmitted to the screen indirectly so that the reciprocating rod is not directly connected to the screen surface, and in this connection to provide spring cushioning means between the rod and the 15 screen and provide bumper blocks against which the yoke impacts at opposite portions of the stroke so as to thereby jar the screen and thus cause all the material lying upon the screen and having a tendency to remain 20 in the screen openings to be jarred out, thus preventing "blinding" of the screen and also giving the material upon the screen a rapid travel across it and increasing the capacity of the screen.

25 A further object is to provide means whereby the length of stroke may be adjusted and the force of impact controlled and thus secure a better action for the cleaning of the screen surface.

30 Other objects will appear in the course of the following description.

My invention is illustrated in the accompanying drawings wherein:

35 Figure 1 is a front elevation of a screen vibrating mechanism constructed in accordance with my invention;

Fig. 2 is a section on the line 2-2 of Figure 1;

40 Fig. 3 is a fragmentary elevation of the upper portion of the vibrating mechanism showing a slight modification.

45 Referring to these drawings 10 designates the screen frame upon which the screen 11 is supported, this screen being of any usual or suitable character and held at its edges by clamps 12 and tension bolts 13. This screen may be disposed in a vertical position, a horizontal position or any other desired position. The screen frame includes 50 two parallel angle irons 14 and passing between these angle irons is the eccentric rod 15 which, at its upper end, is connected to

the eccentric ring 16 operated by the eccentric 17. This rod 15, therefore, reciprocates. The eccentric rod passes loosely 55 through two cross bars 18, 19 which, with the connecting bolts 21, constitute a yoke. These connecting bolts 21 pass through the ends of the several cross bars and are engaged by nuts 22 disposed on each side of 60 each cross bar and which with the cross bars may be held in spaced relation to each other. The cross bars 18 and 19 are disposed respectively above and below the beams 14 of the screen frame. 65

Passing through relatively large apertures in the cross bars 18 and 19 is the eccentric rod 15. The inner end of this eccentric rod carries the nut 23. Mounted upon this nut is the head 24 and confronting the head 24 70 is a head 25 which bears against the under face of the cross bar 19. Supported by these heads, which are flanged, is the coiled compression spring 26. Disposed against the upper face of the cross bar 18 is the head 75 27 and confronting this head and mounted for adjustment upon the screw-threaded eccentric rod is the head 28, held in its adjusted position by means of a nut 29. The head 24 is also screw-threaded upon the rod. 80 Disposed between the heads 27 and 28 is the coiled compression spring 30.

85 Connecting the screen 11 and the cross bar 20 is a screw-threaded connecting rod 31 which has nuts engaging the bar 20 and the screen. Disposed upon the upper and lower faces of the beams 14 are the rubber bumper blocks 32 and 33. While I have described the head 28 as being adjustably mounted upon the eccentric rod, I do not 90 wish to be limited to this as the eccentric rod, as shown in Figure 3, might pass loosely through this head and the head be held against upward movement by means of lugs 95 34 extending out from the supports 35 for the eccentric shaft 36, these lugs 34 being provided with adjusting screws 37 which engage the head 28 and resist upward movement of this head.

100 It will be particularly noted that the eccentric rod is in no way connected to the screen cloth except through the action of the springs and that by the adjustment of the nuts 22 the bumpers or transverse bars

18 and 19 of the yoke can be adjusted closer to or further away from the rubber cushions 32 and 33. This will increase or decrease the length of stroke or vibration of the screen. The length of the stroke and the force of the blow is also dependent on the amount of tension in the springs which can be regulated by means of the nuts 29 and 23 or by the adjustment of the screws 37. 10 If a softer impact is desired, the tension of springs can be lessened and the bumpers 18 and 19 adjusted for the length of stroke desired. The force of the blow imparted to the screen can also be varied by varying the 15 hardness of the cushions 32 and 33. This is a very desirable feature as different products require different impacts and lengths of stroke.

In the operation of this mechanism it will 20 be seen that a reciprocating action is given to the rod 15 and when the rod moves upward, the bumper block 19 will be forced against the rubber cushion 33 by means of the spring 26. This upward movement of the 25 yoke moves the upper bumper or cross bar 18 away from the rubber cushion 32. The lower bumper 19 strikes against the cushion 33 and this causes a sudden stoppage of the upward movement of the screen. 30 This stoppage occurs before the eccentric has reached its maximum upward movement and from this point there is an interval of time before the eccentric reaches its maximum upward movement and the beginning 35 of its downward movement which permits the material upon the screen surface to be jarred out of the screen openings. The distance the eccentric rod moves upward over the distance required to bring the bumper 40 into contact with the rubber cushion is absorbed by the compression of spring 26. On the downward stroke of the eccentric rod, the tension upon spring 26 is relaxed and head 28 presses upon spring 30 which in 45 turn presses against head 27 and bumper 18 which through the yoke presses the screen surface down and then bumper 18 is suddenly stopped by rubber cushion 32, which 50 stoppage vibrates the screen surface, jars particles through screen openings and spreads the material over the screen surface. The eccentric rod 15 has not yet reached its maximum downward movement when the bumper 18 has been stopped by rubber 55 cushion 32 and its further downward movement is absorbed by the compression of spring 30. This permits of an interval of time before the upward movement of the eccentric begins.

60 The following description of the working of the screen mechanism refers to the action of the mechanism as modified by the construction outlined in Figure 3.

In the operation of this mechanism it will 65 be seen that a reciprocating action is given

to the rod 15 and when the rod moves upward, the bumper 19 will be forced against the rubber cushion 33 by means of the spring 26. This upward movement of the yoke compresses the upper spring 30 and the upper bumper 18 moves away from the rubber cushion 32. The lower bumper 19 will strike against the cushion 33 and this causes a sudden stoppage of the movement of the screen and vibrates the screen. On the downward stroke of the eccentric rod 15, the tension on the lower spring 26 is relaxed and the spring 30 now being stronger than the spring 26, forces the bumper 18 to strike the cushion 32, and a second jar is given to the screen.

The particular merits of this mechanism lie in the exceptionally snappy action which is given to the screen surface brought about by the fact that upon the upward movement of the eccentric rod, the screen is not only raised but is stopped suddenly by the impact of the yoke against the rubber cushion 32. The result of this is that all material lying upon the screen and having a tendency to clog or remain in the screen openings is bumped out, thus preventing any clogging of the screen. This sudden jar communicated to the screen gives the material upon the screen a rapid travel across it and increases the capacity of the screen. This same action occurs upon the downward movement of the eccentric rod and thus two jars are given to the screen upon each reciprocation of the rod. The main feature which makes this screen vibrating mechanism particularly valuable is that the eccentric is not directly connected to the screen surface but is connected through a yoke and opposed springs and thus adjustment for length of stroke may be secured and second, the force of the impact may be controlled, thus preventing any "blinding" of the screen. This sudden stoppage also has the effect of giving concentric waves of vibration to the screen surface which operates during the intervals of time for completing the eccentric's maximum upward and downward movements which operate to increase the efficiency and capacity over a screen surface simply pulled up and down with a straight eccentric movement.

I claim:—

1. In a mechanism of the character described an element to be reciprocated, a reciprocating rod, a yoke connected to the element and including a bumping element through which the rod loosely passes, springs carried by the rod and bearing against opposite faces of the bumping element to thus resiliently transmit movement of the rod to said yoke, and cushions disposed in the path of movement of said bumping element on opposite sides thereof, the bumping element and the cushions being

relatively adjustable toward or from each other.

2. In screen operating mechanism, a reciprocating rod, a yoke adapted to be connected to a member to be reciprocated and including spaced parallel bumping members through which bumping members the rod loosely passes, springs carried by the rod and bearing against the opposite faces of the bumping members to thus resiliently transmit the movement of the rod to said yoke, and cushions disposed in the path of movement of said bumping members.

3. In screen operating mechanism, a reciprocating rod, a yoke adapted to be connected to a member to be reciprocated and including spaced parallel bumping members through which bumping members the rod loosely passes, springs carried by the rod and bearing against the opposite faces of the bumping members to thus resiliently transmit the movement of the rod to said yoke, and cushions disposed in the path of movement of said bumping members, the bumping members being adjustable toward or away from each other and the cushions.

4. In a screen operating mechanism, a reciprocating rod, a yoke adapted to be adjustably connected to a member to be reciprocated and including two parallel transversely extending bumpers, bolts connecting said bumpers whereby the bumpers may be adjusted toward or away from each other, oppositely disposed parallel beams extending between the bumpers and rigidly supported, the upper and lower faces of the beams carrying cushions, the reciprocating rod passing loosely through the bumpers, and coiled springs surrounding said rod above and below the bumpers and each bearing against the adjacent bumper, the tension of said springs being adjustable.

5. In a screen operating mechanism, a reciprocating rod, a yoke adapted to be adjustably connected to a member to be reciprocated and including two parallel transversely extending bumpers, bolts connecting said bumpers whereby the bumpers may be adjusted toward or away from each other, oppositely disposed parallel beams extending between the bumpers and rigidly supported, the upper and lower faces of the beams carrying cushions, the reciprocating rod passing loosely through the bumpers, and coiled springs surrounding the rod and disposed above and below the bumpers and each bearing against one of the bumpers, and means for adjustably supporting the

ends of the springs remote from the bumpers.

6. In screen operating mechanism, a reciprocating rod, a yoke adapted to be adjustably connected to a member to be reciprocated and including two parallel transversely extending bumpers, bolts connecting said bumpers whereby the bumpers may be adjusted toward or away from each other, oppositely disposed parallel beams extending between the bumpers and rigidly supported, the upper end and lower faces of the beams carrying cushions, the reciprocating rod passing loosely through the bumpers, and coiled springs surrounding the rod and disposed above and below the bumpers, and each bearing against one of the bumpers, means for supporting one of said springs comprising a head adjustably mounted upon the reciprocating rod, and means for adjustably supporting the end of the other spring remote from the bumper comprising lugs and screws passing through said lugs, and a head engaging the proximate end of a spring and against which said screws engage.

7. In screen operating mechanism, spaced cross beams, a shaft disposed above the beams, an eccentric mounted upon the shaft, an eccentric rod extending down between said beams, a yoke connected to the eccentric rod and adapted to be connected to a member adapted to be reciprocated, said yoke comprising a pair of spaced parallel bumpers disposed respectively above and below the cross beams, and a cross bar operatively connected to the screen, bolts connecting said bumpers and the cross bar to each other and extending between the cross beams, the bumpers and the cross bar being adjustable toward or from each other upon said bolts, rubber cushions mounted upon the cross beams and confronting the bumpers, a spring surrounding the lower end of the rod, upper and lower heads against which the opposite ends of the spring bear, one of said heads being adjustable to tension the spring, an upper coiled spring surrounding the upper portion of the eccentric rod and operatively supported at its lower end against the upper bumper, a head supporting the upper end of the spring, and means for adjusting said head toward or from the corresponding bumper to thereby tension the spring.

In testimony whereof I hereunto affix my signature.

EDWARD HASKINS SHACKELFORD, Jr.
